UNITED STATES PATENT OFFICE

151,481

DESIGN FOR AN EELSKIN RIG FOR BASS

John Williamowicz, Worcester, Mass.

Application January 2, 1947, Serial No. 135,891

Term of patent 7 years

(Cl. D31—4)

To all whom it may concern:

Be it known that I, John Williamowicz, a citizen of the United States, residing at Worcester, in the county of Worcester, and State of Massachusetts, have invented a new, original, and ornamental Design for an Eelskin Rig for Bass, of which the following is a specification, reference being had to the accompanying drawing, forming part thereof.

Fig. 1 is a side elevational view of an eelskin rig, showing my new design;

Fig. 2 is a front elevational view, taken from the left in Fig. 1;

Fig. 3 is a sectional side elevation, taken along the line 3—3 in Fig. 5;

Fig. 4 is a fragmentary front elevation, looking in the direction of the arrow 4 in Fig. 1; and

Fig. 5 is a sectional plan view, taken along the line 5—5 in Fig. 2.

I claim:

The ornamental design for an eelskin rig for bass, as shown.

JOHN WILLIAMOWICZ.
